(57) **CLAIM**

The ornamental design for a drum leg, as shown and described.

DESCRIPTION

FIG. 1 is a perspective view of a drum leg showing my new design;

FIG. 2 is a front elevational view thereof, the rear elevational view being a mirror image thereof;

FIG. 3 is a left side elevational view thereof, the right side elevational view being a mirror image thereof;

FIG. 4 is a top plan view thereof;

FIG. 5 is a bottom plan view thereof; and,

FIG. 6 is a vertical cross-sectional view thereof taken along line 6—6 of FIG. 2.

1 Claim, 2 Drawing Sheets

FIG. 4

FIG. 5

FIG. 1

FIG. 6

FIG. 3

FIG. 2
